UNITED STATES PATENT OFFICE

2,371,951

DOUBLE DIAPHRAGM LOUD-SPEAKER

Ellsworth D. Cook, Scotia, N. Y., assignor to General Electric Company, a corporation of New York

Application January 7, 1943, Serial No. 471,576

2 Claims. (Cl. 179—115.5)

My invention relates to acoustic devices of the dynamic type for transmitting signals over both low and high ranges of frequencies, particularly to loudspeaker or like devices employing two diaphragms of different size and characteristics for respectively transmitting a low and a high frequency range, and its principal object is to provide an improved acoustic device of the two-diaphragm type.

It is well known from experience with developments in the acoustic prior art involving various forms of diaphragms, particularly the large diameter cone diaphragms employed in dynamic loudspeakers, that it is difficult practically, even if not impossible theoretically, so to construct a single diaphragm that it may be forced satisfactorily to operate over an extremely extended frequency range, such a range for example as one comprising both the high frequency portion and the low frequency portion of the voice range.

At least part of the difficulty is to be found in the excessive mass loads imposed at the high frequencies on the voice coil. The loads imposed are practically prohibitive at high frequencies if it be attempted so to construct the large diameter diaphragm structure which is capable of moving integrally as a piston at low frequencies and especially adapted to transmission of these low frequencies, that it will also be capable of transmitting the high frequencies while moving as a piston. The practical result of this difficulty when employing the single diaphragm is that a certain amount of elasticity in the diaphragm, avoiding the piston action of the diaphragm as a unit at the high frequencies, is usually unavoidable, it being thus found necessary to permit wave action in the diaphragm in order to transmit the high frequencies at all adequately without excessive loading of the driving coil.

It is a further and particular object of my present invention to provide an improved two-diaphragm acoustic device wherein loading of the driving winding by the mass of the low frequency diaphragm system at the high frequency range of operation is prevented.

In accordance with my present invention the above noted difficulties are overcome and the above noted and other objects attained by the provision of a double diaphragm device of special arrangement, but which in appearance is not extremely dissimilar to the conventional form of cone diaphragm loudspeaker. In an acoustic device in accordance with the invention, the diameter of the operating winding or voice coil for the diaphragm is increased somewhat over

that of conventional forms, and an inverted diaphragm of general cone shape and of approximately the diameter of the voice coil is rigidly attached thereto. A relatively large diameter cone diaphragm which is of usual form is also connected to the voice coil, but the connection to this large diaphragm is through an elastic coupling. The mass of the cone structure comprising the large diaphragm, and the elasticity of its coupling to the voice coil, are so proportioned and arranged that the vibratory mechanical system constituted by the large cone structure is adjusted to respond to the vibratory energy supplied by the voice coil over only the desired low frequency portion of the voice range.

The novel features which are considered characteristic of my invention are set forth with particularly in the appended claims. My invention itself, however, both as to its organization and method of operation together with further objects and advantages thereof may best be understood by reference to the following description taken in connection with the accompanying drawing, the single figure of which is a cross-sectional fragmentary view of an acoustic device in which my invention has been embodied.

Referring to the single figure of the drawing, the acoustic device which is shown therein for illustrative purposes is essentially similar to a conventional dynamic loudspeaker, the numeral 10 designating a large cone diaphragm which may be of usual diameter at its outer end, for example 8 to 14 inches. The diaphragm 10 is provided with suitable suspension means, comprising a usual flexible ring 11 which may be secured to a fixed frame element (not shown). A second diaphragm 12 is provided which is of substantially less diameter than that of the diaphragm 10, of the order of one-half, for example, and which 40 is mounted in inverted relation with the latter diaphragm at the smaller end thereof. The diaphragm 12 is fitted like a cap adjacent the outer side of a voice coil 13 and extending within the larger diaphragm. The diaphragm 12 is of a general cone shape, but while it may be a cone as illustrated, it may also be of somewhat different configuration, as cup or dome-shaped or otherwise rounded or flattened, if desired, for construction reasons. The exact shape of diaphragm 50 12 is important only from a design or structural standpoint. An advantage found in the illustrated inverted positioning of the smaller diaphragm 12, whatever be its exact form, resides in the fact that the inverted diaphragm spreads the high frequencies over a somewhat wider solid an-

gle than would be obtained with the conventional placing of a cone diaphragm.

For driving the two diaphragms 10 and 12, the diaphragm operating winding 13, which is a usual voice coil if the acoustic device is employed for converting electrical oscillations into sound, may be connected to a suitable oscillation source (not shown). The voice coil is mounted in a usual manner on a cylindrical support 14 to vibrate in an air gap 15 between poles 16 and 17 of a field magnet, only the poles of which are shown in the drawing. The voice coil 13 is desirably of considerably larger diameter than is usual practice, and is preferably of approximately the diameter of the smaller diaphragm 12.

The smaller diaphragm 12 is so mounted as to be driven or vibrated directly by the voice coil as by securing the edge 18 of the latter diaphragm rigidly to the outer end 19 of the coil support 14. The larger diaphragm 10, however, is not arranged to be driven or vibrated directly by the voice coil 13 but through an elastic coupling. For this purpose the coil 13 and diaphragm 10 are preferably operatively associated with each other by means of an elastance element 20 which may be in the form of a ring of pliant material, the sides 21 and 22 of which are secured respectively to the voice coil support 14 and to the smaller edge 23 of the diaphragm 10, and which comprises a fold of Sylphon bellows-like form 24.

To provide suitably larger diameter mounting space for the voice coil 13 which is preferably of considerably larger diameter than in usual practice, the inner core or pole piece 17 of the magnet system may be provided with an extension piece 25 of larger diameter, and the central opening in the outer pole piece 16 may be of correspondingly larger diameter to provide the required larger diameter air gap 15.

In operation of the acoustic device illustrated in the drawing, assuming that the device is operating in the high frequency portion of the voice range, then since the broadly tuned mechanical vibratory system, constituted by the coupling elastance 24 and the mass of the cone structure comprising the larger cone 10, responds only over the predetermined low frequency portion of the voice range, all of the high frequency portion of the range is therefore transmitted only from the smaller diaphragm 12. When on the other hand the device is operating in the low frequency portion of the range, although the smaller diaphragm 12 then vibrates together with the larger diaphragm 10 being rigidly secured at all times to the coil coil, nevertheless the larger diaphragm 10 responds to and transmits substantially all of this low frequency portion of the voice range.

Therefore in operation of the acoustic device embodying my invention, the mass of the low frequency system including the larger cone 10 is prevented from becoming a load on the voice coil 13 when the acoustic device is operating on the high frequency portion of the voice range. This mass, it will be noted, would become a load on the voice coil if the mass were vibrated over the entire

frequency range of the device, and would necessitate either a driving system of much higher power at the high frequencies or might even under the above assumption refuse to vibrate in the absence of the elastic coupling 20 forming part of the tuned mechanical vibratory system comprising the larger cone structure.

The diameter of the smaller or high frequency diaphragm 12 has been shown herein as approximately that of the voice coil 13, and also shown as of the order of one-half that of diaphragm 10. It will be understood, however, that the diameter of diaphragm 12 while not especially critical should be such in any case that this diaphragm may have sufficient total radiation resistance to radiate the full amount of high frequency energy required. Otherwise stated, it is therefore the maximum value of this high frequency energy which is a factor in determining the dimensions of the high frequency diaphragm.

My invention has been described herein in a particular embodiment for purposes of illustration. It is to be understood, however, that the invention is susceptible of various changes and modifications and that by the appended claims I intend to cover any such modifications as fall within the true spirit and scope of my invention.

What I claim as new and desire to secure by Letters Patent of the United States is:

- 30 1. In combination, in a dynamic type loudspeaker, a truncated cone-shaped diaphragm of relatively large diameter for transmitting a relatively low range of frequencies, an operating winding approximately one-half the larger diameter of said diaphragm, said cone-shaped diaphragm having a smaller diameter approximately one-half its larger diameter, an inverted diaphragm of approximately the same diameter as said winding connected thereto for transmitting a maximum amount of energy at a relatively high range of frequencies, and elastance means connecting said winding to said first-named diaphragm for preventing the mass of said first-named diaphragm from loading said winding at said high frequency.
- 35 2. In combination, in a dynamic type loudspeaker, a truncated cone-shaped diaphragm of relatively large diameter for transmitting a relatively low range of frequencies, an operating winding approximately one-half the larger diameter of said diaphragm, said cone-shaped diaphragm having a smaller diameter approximately one-half its larger diameter, an inverted diaphragm of approximately the same diameter as said winding connected thereto for transmitting a maximum amount of energy at a relatively high range of frequencies, and a bellows-like elastance element connecting said winding and said first-named diaphragm for preventing the voice
- 40 3. In combination, in a dynamic type loudspeaker, a truncated cone-shaped diaphragm of relatively large diameter for transmitting a relatively low range of frequencies, an operating winding approximately one-half the larger diameter of said diaphragm, said cone-shaped diaphragm having a smaller diameter approximately one-half its larger diameter, an inverted diaphragm of approximately the same diameter as said winding connected thereto for transmitting a maximum amount of energy at a relatively high range of frequencies, and elastance means connecting said winding to said first-named diaphragm for preventing the mass of said first-named diaphragm from loading said winding at said high frequency.
- 45 4. In combination, in a dynamic type loudspeaker, a truncated cone-shaped diaphragm of relatively large diameter for transmitting a relatively low range of frequencies, an operating winding approximately one-half the larger diameter of said diaphragm, said cone-shaped diaphragm having a smaller diameter approximately one-half its larger diameter, an inverted diaphragm of approximately the same diameter as said winding connected thereto for transmitting a maximum amount of energy at a relatively high range of frequencies, and a bellows-like elastance element connecting said winding and said first-named diaphragm for preventing the mass of said first-named diaphragm from loading said winding at said high frequency range, said element being constructed and arranged to transmit substantially all the low frequency energy passing from said winding to said first diaphragm along paths parallel to the central axis of said first diaphragm.
- 50 5. In combination, in a dynamic type loudspeaker, a truncated cone-shaped diaphragm of relatively large diameter for transmitting a relatively low range of frequencies, an operating winding approximately one-half the larger diameter of said diaphragm, said cone-shaped diaphragm having a smaller diameter approximately one-half its larger diameter, an inverted diaphragm of approximately the same diameter as said winding connected thereto for transmitting a maximum amount of energy at a relatively high range of frequencies, and elastance means connecting said winding to said first-named diaphragm for preventing the mass of said first-named diaphragm from loading said winding at said high frequency range, said element being constructed and arranged to transmit substantially all the low frequency energy passing from said winding to said first diaphragm along paths parallel to the central axis of said first diaphragm.
- 55 6. In combination, in a dynamic type loudspeaker, a truncated cone-shaped diaphragm of relatively large diameter for transmitting a relatively low range of frequencies, an operating winding approximately one-half the larger diameter of said diaphragm, said cone-shaped diaphragm having a smaller diameter approximately one-half its larger diameter, an inverted diaphragm of approximately the same diameter as said winding connected thereto for transmitting a maximum amount of energy at a relatively high range of frequencies, and a bellows-like elastance element connecting said winding and said first-named diaphragm for preventing the mass of said first-named diaphragm from loading said winding at said high frequency range, said element being constructed and arranged to transmit substantially all the low frequency energy passing from said winding to said first diaphragm along paths parallel to the central axis of said first diaphragm.
- 60 7. In combination, in a dynamic type loudspeaker, a truncated cone-shaped diaphragm of relatively large diameter for transmitting a relatively low range of frequencies, an operating winding approximately one-half the larger diameter of said diaphragm, said cone-shaped diaphragm having a smaller diameter approximately one-half its larger diameter, an inverted diaphragm of approximately the same diameter as said winding connected thereto for transmitting a maximum amount of energy at a relatively high range of frequencies, and elastance means connecting said winding to said first-named diaphragm for preventing the mass of said first-named diaphragm from loading said winding at said high frequency range, said element being constructed and arranged to transmit substantially all the low frequency energy passing from said winding to said first diaphragm along paths parallel to the central axis of said first diaphragm.
- 65 8. In combination, in a dynamic type loudspeaker, a truncated cone-shaped diaphragm of relatively large diameter for transmitting a relatively low range of frequencies, an operating winding approximately one-half the larger diameter of said diaphragm, said cone-shaped diaphragm having a smaller diameter approximately one-half its larger diameter, an inverted diaphragm of approximately the same diameter as said winding connected thereto for transmitting a maximum amount of energy at a relatively high range of frequencies, and a bellows-like elastance element connecting said winding and said first-named diaphragm for preventing the mass of said first-named diaphragm from loading said winding at said high frequency range, said element being constructed and arranged to transmit substantially all the low frequency energy passing from said winding to said first diaphragm along paths parallel to the central axis of said first diaphragm.

ELLSWORTH D. COOK.
